UNITED STATES PATENT OFFICE.

HARRY ANDREW TAYLOR, OF NEW YORK, N. Y.

GLOVE.

1,256,391.

Specification of Letters Patent. Patented Feb. 12, 1918.

Application filed September 11, 1917. Serial No. 190,735.

To all whom it may concern:

Be it known that I, HARRY A. TAYLOR, a citizen of the United States, and a resident of the city of New York, borough of Manhattan, in the county and State of New York, have invented a new and Improved Glove, of which the following is a full, clear, and exact description.

Among the principal objects which the 10 present invention has in view are: to avoid damaging the border or finished facing about the wrist openings of gloves; to secure the facing about said wrist openings with an extensible means for fastening the edge of 15 the facing to the glove; and to impart a neat and workmanlike appearance to a glove having the binding facing for the wrist opening.

Drawings.

20 Figure 1 is a perspective view of a glove constructed and arranged in accordance with the present invention;

Fig. 2 is a perspective view on an enlarged 25 scale, showing a fragment of the wrist opening and means for securing the edge of the reinforcing portion thereof;

Fig. 3 is a section taken as on the line 3—3 in Fig. 2;

30 Fig. 4 is a pictorial view showing the stitches securing the inner edge of the binding piece as yielding to a stretching strain.

Description.

35 Heretofore the wrist openings of gloves have been reinforced by securing adjacent the edge and at the inner side of the glove, a binding or facing strip of material. The

material has or has not resembled in color and texture the body of the glove. The 40 stitching employed for securing the facing or binding material rendered the material non-extensible. This has resulted in straining the glove structure in the endeavor to close the glove until the stitching 45 has broken and the ends separated sufficiently to leave a gap where the material has been parted. The raw edge of the binding when not secured produces an unfinished appearance to the glove.

50 Gloves when constructed in accordance with the present invention are provided with a binding strip 9, the outer edge of which is held by the usual line of stitching 10. The inner edge of the strip 9 is secured to the 55 body 11 of the glove by a row of hemstitching 12. The hemstitching provides a series of openings 13 formed by overcast stitches at the sides thereof in line with the direction of the stitching. This form of 60 stitching while securing the raw edge of the binding strip 9 yields to the strain of the material parallel with the line of stitching and thus avoids the breaking away of the 65 stitching and consequent loosening of the edge of the binding strip 9.

Claim.

A glove having a wrist opening, a binding strip for said glove at said wrist opening, 70 means embodying stitching for uniting the outer edge of said strip with the body of said glove, and open-centered hemstitching for uniting the inner edge of said strip with the body of said glove.

HARRY ANDREW TAYLOR.
